Primary Examiner — Dana K Weiland*Assistant Examiner* — Messina L Smith(74) *Attorney, Agent, or Firm* — Cantor Colburn LLP(57) **CLAIM**

The ornamental design for a hair dryer, as shown and described.

DESCRIPTION

FIG. 1 is a perspective view of a hair dryer showing my new design;
FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top plan view of FIG. 1; and,

FIG. 7 is a bottom view of FIG. 1.

The broken lines in the drawings are for the purpose of illustrating portions of the hair dryer that form no part of the claimed design.

1 Claim, 7 Drawing Sheets(56)
